UNITED STATES PATENT OFFICE.

JULIUS J. MILLER, OF ST. JOSEPH, MICHIGAN, ASSIGNOR, BY MESNE ASSIGNMENTS, TO WIREBOUNDS PATENTS COMPANY, OF KITTERY, MAINE, A CORPORATION OF MAINE.

WIRE-BOUND CRATE OR BOX BLANK MACHINE.

1,191,111.

Specification of Letters Patent.

Patented July 11, 1916.

Application filed June 28, 1911. Serial No. 635,787.

To all whom it may concern:

Be it known that I, JULIUS J. MILLER, a citizen of the United States of America, and resident of St. Joseph, Berrien county, Michigan, have invented a certain new and useful Improvement in Wire-Bound Crate or Box Blank Machines, of which the following is a specification.

My invention relates to machinery for making wire bound crates or boxes of that particular character in which the blanks are reinforced by cleats secured along the edges thereof, and in which the different sections of the foldable blank are flexibly connected together by means of binding wires, the said wires being secured to the veneer or other sheet material of the blank by the same staples that secure the said veneer or sheet material to the said cleats.

Broadly considered, my invention contemplates a machine for making blanks of the foregoing general character in which a traveling work-holder is provided for supporting the cleats and veneer in properly spaced and crossed relation, and in which the feed mechanism for causing the assembled materials to move forward in a step by step manner, below the staplers by which the binding wires and sheets of veneer are secured to the cleats, is provided with teeth or similar means for engaging the materials of the blank, whereby the feeding motion is transmitted through the blank or blank materials to the said work-holder, as distinguished from previous machines in which a traveling work-holder of this character is employed for communicating the feeding motion to the blank or blank materials, as will hereinafter more fully appear.

More specifically considered, my invention contemplates a blank machine of this general character in which an endless traveling work-holder is employed for merely supporting and positioning the blank materials, but not for feeding the said materials forward below the staplers, this feeding motion or step by step advancement of the materials being accomplished by a feeding mechanism which is located above the path of travel of the blanks or blank materials, and which is provided with a plurality of link belts having teeth which engage the upper surface of the veneer or other sheet material of the blanks, whereby the said work-holder is moved or operated by the

feeding motion of the blanks, as distinguished from prior machines in which the blanks or blank materials are moved or fed forward below the staplers by the actuation of the said work-holder, as will hereinafter more fully appear.

In the accompanying drawings—Figure 1 is a side elevation of a wire bound crate or box blank machine embodying the principles of my invention. Fig. 2 is a plan of the said machine. Fig. 3 is an enlarged detail sectional view of one of the hand wheels and screw threaded shaft arrangement for adjusting the machine for blanks of different width. Fig. 4 is a longitudinal section on line 4—4 in Fig. 2. Fig. 5 is an enlarged detail cross section of one of the endless traveling link belts which are employed for supporting and carrying the blanks or blank materials, showing also in cross section the guide or channel bar upon which the said link belt slides. Fig. 6 is an enlarged perspective of a spacing block of the kind suitable for blanks shown in Figs. 1, 2 and 4. Fig. 7 is a view similar to Fig. 1, showing a different form of my invention. Fig. 8 is a perspective of one of the spacing blocks employed on the endless traveling work-holder of the machine shown in Fig. 7. Fig. 9 is a perspective of a box blank.

As thus illustrated, and referring to Figs. 1 to 6, inclusive, it will be seen that my invention comprises a base A upon which are mounted the castings or uprights B, C and D of the frame or body, these castings being arranged in pairs, one at each side of the said base. The uprights C and D support the shafts c, and d, upon which are mounted the sprockets c' and d' for the endless link belts E. The upper portions of these link belts travel in guides or channel bars e, and each chain or link belt is composed of links which are provided on their sides with pockets or channels e' to receive the cleats 1 of the box blank. The staplers F by which the binding wires 2 are secured to the blank, and by which the veneer 3 is secured to the cleats 1 (see Fig. 9), are arranged in a row on the stationary head or cross bar f, in the usual manner, and are operated by the upper cross head f', which latter slides up and down in the slots f² in the upper portions of the said uprights B. A cross bar G connects the two uprights B, at a point below the said staplers, and is provided with means of

the usual character for supporting the blanks against the impact or pressure of the said staplers. The cross head f' is operated by pitmen G' which have their lower ends 5 suitably connected with and operated by the main operating shaft g .

As shown in Figs. 1, 2 and 4, the box blank materials are placed on the traveling carrier or work-holder composed of the 10 chains E at the right hand end of the machine, and are then allowed to travel with the said work-holder below the said staplers. In front of the said staplers a feed mechanism H is provided for engaging the tops 15 of the blank to move the same and the said work-holder along in a step by step manner. The said feed mechanism is composed of link belts h having teeth h' which engage the upper surfaces of the blanks, and which 20 thereby move the same along, causing the said work-holder to move at the same time. These link belts h are mounted on sprockets h^2 that are suitably secured to shafts h^3 which extend transversely of the machine. 25 These two shafts have their ends supported in bearings h^4 that are vertically movable in castings or brackets carried by the frame of the machine. These bearings h^4 are held down by springs h^5 , the tension of which 30 may be adjusted by said screws h^6 , whereby the pressure of the said feed mechanism on the blanks may be varied or regulated at will. This feed mechanism is operated by a ratchet device I , connected with the shaft 35 h^3 nearest the staplers, the said ratchet mechanism being in turn operated by a pitman i having its lower end suitably connected with and operated by the main operating shaft g . It will be understood that the 40 connection of the pitmen G' with the shaft g and the connection of the pitman i with the shaft g are so relatively adjusted that the feed mechanism H is actuated to feed the materials forward at a time when the 45 staplers are elevated or away from the work. When the motion of the said staplers is reversed, the feed mechanism H then stands still and the staplers move downward to insert staples in the blank materials. These 50 staplers are inserted crosswise of the binding wires 2, and are long enough to extend through the veneer and into the cleats. The step by step movement communicated to the blank materials is also communicated 55 to the work-holder consisting of the endless link belts E , as the pressure of the feed mechanism against the blank materials is sufficient to move the work-holder by friction. 60 The ends of the cleats can be spaced apart by spacing blocks of the kind shown in Fig. 6, if loose blocks J are desired for this purpose, or by blocks of the kind shown in Fig. 8, if it be desired to have the said blocks K secured to the said chains or link belts E .

If the blocks K are employed, it will be seen that the ribs k thereof fit the channels k' in the sides of the pockets or channels e' of the link belts, and that by tightening the nuts k^2 on the said link belts the said spacing 70 blocks can be secured at any desired position in the said link belts, according to the length of the cleats. If the blocks J are used, then it will be seen that the ribs k are not necessary, and that the tightening of the 75 nuts k^2 is not necessary as the said blocks are left loose in the channels of the work-holder, and are easily adjusted for cleats of different lengths. The lower portions of the chains or link belts h are held against 80 the blanks, or the blank materials, by the bars h' , or by any other suitable means, whereby the feed mechanism takes a good grip on the materials. These bars can be made adjustable in any suitable manner, as 85 by mounting them on the shafts h^3 , so that their pressure on the said chains or link belts h can be varied or regulated at will.

The shafts c , d and h^3 are threaded to receive the sprockets for one of the belts E , 90 and for one of the belts H , which sprockets are controlled by hand wheels L on the shafts c and d , and by similar hand wheels M on the shafts h^3 , the construction in each case being of the character shown in Fig. 3, 95 in which it will be seen that each shaft is provided with a longitudinal groove in which a spline N is arranged to slide, which spline or feather secures the sprocket to the shaft. The sprocket has a hub n which rotates in the grooved hub n' of the hand wheel, said hand wheel having a screw-threaded engagement with the said shaft. Thus by rotating the hand wheel, the hub 100 can be moved along the length of the shaft, and the shaft and sprocket and hand wheel will rotate at any adjusted position thereof. Thus the machine can be adjusted for any desired width of blank. This method of adjustment is, however, old and well known; 110 as it has been used in prior box blank machines, and does not require any further description.

In Fig. 7, the construction is substantially the same as that previously described and 115 shown, except in this case the feed mechanism O is arranged at the delivery end of the machine, instead of at the end where the materials are placed on the traveling work-holder. The said feed mechanism is 120 exactly the same as that shown in the previous figures, and such as already described, but operates on the finished blank instead of on the loosely assembled blank materials. The teeth of the feed mechanism O engage 125 the tops of the blanks as they emerge from under the staplers, and in this case the spacing blocks are preferably secured to the traveling work-holder in order to insure 130 against slippage between the work and the

said traveling work-holder. In the previous case, and with the feed mechanism on the assembling side of the staplers, loose spacing blocks can be employed in the manner previously explained. But with the feed mechanism on the delivery side of the staplers it is preferable, as stated, to employ spacing blocks which are secured to the chains or link belts E of the traveling work-holder. Otherwise, the two machines are substantially alike. In each case the traveling work-holder is moved by the blanks, or by the blank materials, as distinguished from previous machines in which the blanks or blank materials are moved by the traveling work-holder. The feeding motion is, therefore, communicated directly to the blanks or the blank materials, and through these blanks or blank materials to the traveling work-holder.

The construction of the link belts or chains E of the traveling work-holder can be of any suitable, known or approved character. As shown, they are of the kind heretofore employed in machines for making crate or box blanks of this kind. Guards or plates or bars, or other like devices, can be employed for preventing the blanks or blank materials from becoming displaced from the work-holder, it being common to employ such means for engaging the tops of the blanks or blank materials near the outer edges thereof to accomplish this purpose. This, of course, is not necessary where the blanks or blank materials pass under the feed mechanism H, or under the feed mechanism O, as the case may be.

From the foregoing it will be seen that I provide a simple and highly efficient machine for making wire bound crate or box blanks, in which the feeding motion is communicated directly to the blanks or blank materials, and not through the traveling work-holder by which the said materials are supported in properly spaced and crossed relation.

What I claim as my invention is:

1. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provisions for securing the binding wires to said sheets and cleats, and feed mechanism for engaging the blank materials to communicate the feeding motion to said blocks and belts.

2. A machine for making wire bound box blanks by wiring together the sheets and cleats of the previously unconnected side sections of each blank, comprising a plurality of endless belts, blocks for spacing the

adjacent ends of the cleats at intermediate points in each blank, and at the ends of each blank, said blocks being carried by said belts, staplers having provisions for securing the binding wires to said sheets and cleats, and feed mechanism for engaging the blank materials to communicate the feeding motion to said blocks and belts, said mechanism including link belts provided with teeth for engaging the sheets.

3. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provisions for securing the binding wires to said sheets and cleats, and feed mechanism for engaging the blank materials to communicate the feeding motion to said blocks and belts, said mechanism including teeth for engaging the upper surface of the sheets.

4. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provisions for securing the binding wires to said sheets and cleats, and feed mechanism for engaging the blank materials to communicate the feeding motion to said blocks and belts, said belts having means for holding said blocks in fixed relation thereon.

5. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provisions for securing the binding wires to said sheets and cleats, and feed mechanism for engaging the blank materials to communicate the feeding motion to said blocks and belts, said mechanism having means for engaging the sheets.

6. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provision for securing the binding wires to said sheets and cleats, and feed mechanism for engaging the

blank materials to communicate the feeding motion to said blocks and belts, and also from said materials to said wires.

7. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each blank, said blocks being carried by said belts, staplers having provision for securing the binding wires to said sheets and cleats, and feed mechanism for engaging the blank materials to communicate the feeding motion to said blocks and belts, the arrangement being such that said belts are stationary except when actuated by said mechanism.

8. A machine for making wire bound box blanks by wiring together the sheets and cleats of the previously unconnected side sections of each blank, comprising a plurality of endless belts, blocks for spacing the adjacent ends of the cleats at intermediate points in each blank, and at the ends of each

blank, said blocks being carried by said belts, staplers having provision for securing the binding wires to said sheets and cleats, and feed mechanism for engaging the blank materials to communicate the feeding motion to said blocks and belts, said mechanism being so constructed and arranged as to engage one section before disengaging another section.

9. A machine for making wire bound box blanks by wiring together the sheets and cleats of the previously unconnected side sections of each blank, comprising a plurality of endless belts provided with means to space the blank sections, devices to apply the binding wire to the sections, and feed mechanism for engaging the blank materials to propel the same and said belts in unison.

Signed by me at St. Joseph, Michigan, this 29th day of May, 1911.

JULIUS J. MILLER.
